The ornamental design for a liquid crystal display housing unit for a slide projector, as shown and described.

DESCRIPTION

FIG. 1 is a front perspective view of a liquid crystal display housing unit for a slide projector embodying our design;

FIG. 2 is a bottom view thereof;

FIG. 3 is a top view thereof;

FIG. 4 is a front elevation thereof;

FIG. 5 is a right side elevation thereof, the left side being a mirror image; and,

FIG. 6 is a rear elevation thereof.
